CLAIM

The ornamental design for a housing for a driver guidance system, as shown and described.

DESCRIPTION

FIG. 1 is a top plan view of the housing for a driver guidance system;

FIG. 2 is a bottom plan view thereof;

FIG. 3 is a top perspective view thereof;

FIG. 4 is a bottom perspective view thereof;

FIG. 5 is a first elevational view thereof;

FIG. 6 is a second elevational view thereof;

FIG. 7 is a third elevational view thereof; and,

FIG. 8 is a fourth elevational view thereof.

The broken lines shown in the drawings depict features that form no part of the claimed design.
